UNITED STATES PATENT OFFICE.

FRANK H. HOUGHLAND, OF HOUSTON, TEXAS.

COLLAPSIBLE BOX.

1,168,072.

Specification of Letters Patent.

Patented Jan. 11, 1916.

Application filed March 9, 1915. Serial No. 13,098.

To all whom it may concern:

Be it known that I, FRANK H. HOUGHLAND, a citizen of the United States, residing at Houston, Harris county, and State 5 of Texas, have invented and discovered certain new and useful Improvements in Collapsible Boxes, of which the following is a specification.

My said invention consists in certain improvements in the construction of collapsible boxes of that type ordinarily constructed of pasteboard, or similar material, for packing purposes, such as are commonly used by tailors, millinery establishments, laundries, 10 etc., whereby such a box is provided having strong and perfect ends adapted to retain their shape and remain closed during use, thus adding materially to the utility of such a box, as well as its advantage in use, 15 all as will be hereinafter more fully described and claimed.

Referring to the accompanying drawings, which are made a part hereof, and on which similar reference characters indicate similar parts, Figure 1 is a perspective view of a box, without its top, illustrating a folding or collapsible box of my improved construction as it appears when ready for use, the interior appearance being illustrated at the 20 right-hand side of said figure, and the exterior appearance at the left-hand side, Fig. 2 a detail top or plan view of the left-hand end of the box when in collapsed position, Fig. 3 a similar view of the right-hand end 25 of the box, showing the blank completely flattened out, ready to be formed, as shown in Fig. 2, Fig. 4 a view of the ends as shown in Fig. 2, with the parts nearly in erected position, Fig. 5 a vertical section through the 30 end of the box, as on the dotted line 5—5 in Fig. 6, Fig. 6 a horizontal section, as on the dotted line 6—6 in Fig. 5, and Fig. 7 a view 35 similar to Fig. 4, showing a modified form.

In forming the box, the blank A, consisting of pasteboard, or similar material, is formed with slits 10 at a distance from each edge equal to the height desired for the sides of the box and extending from the ends, parallel with the sides, into the blank 40 to a point somewhat farther than a distance equal to the height of the box. The blank is formed with creases, or folds, 11 from end to end, which are in line with the slits 10. It is also formed with transverse creases, or 45 folds, 12 extending entirely across the blank from side to side and parallel with its ends and a distance from the ends to intersect

the inner ends of the slits 10. These creases and slits divide the sides 13 and the ends 15 from the main bottom of the box. In each 50 corner of the blank, between the slit 10 on one side and the groove 12 on the other, are corner flaps 16, which are formed with creases, or folds 17 extending from the junction between the fold 12 and the slit 10 to 55 the outer edge of the flap 16 on a line with a fold 18 in the end flap 15, which extends entirely across said end flap at a point which defines the top edge of the box, leaving a flap 20 on the outside thereof. A stiffening 60 member 19 is mounted centrally on the end 15, covering the width of the end from the fold 12 to the fold 18. The flap 20 of the end 15, outside of the fold 18, is adapted to be folded over onto the said stiffening member 19 along the crease 18. The outer ends 65 of the flap 16 are folded along the creases 17 and doubled over onto the part beneath. The sides 13 are then folded over onto the bottom, as shown in Fig. 2, which will bring 70 the part of each flap 16 outside the crease 17 over onto the ends 15, overlapping the ends 75 of the stiffening member 19. After this is done the flap 20 of said ends is folded over, covering said parts 16 and 19 at the upper 80 edge of each end. Staples 21 are then driven through the several parts of the end consisting of the flap 20 and the main end 15, and the flaps 16 and stiffening member 19, one prong of each staple passing through 85 the upper corner of a part 16, as at point 90 22, thus fastening the several parts securely together, as best shown in Figs. 2 and 4. By forming the stiffening member 19 of the full height of the box end it renders said end 95 capable of resisting unusual strain. It will be understood, of course, that said stiffening member may be omitted in boxes where not needed.

Each of the corners 16 has a tongue 23 100 formed therein, as clearly indicated in the drawings, the lower end being free and the upper end left attached to said part 16. When the box is collapsed, as shown in Fig. 2, these tongues will lay flat, but when the 105 box is erected, as shown in Fig. 1, these tongues are brought up around the lower edge of the fold 20 on the box end and inserted through slots 24, formed therein for the purpose, thus fastening said fold and 110 securing the corners of the box from collapsing under strain.

An important part of the locking device of the box consists of the flap 20 formed by

the fold 18 on the end wall 15, in which the slot 24 is formed to receive the tongue 23 of the corner flap 16. Said flap 16 has a diagonal crease or fold 17 extending from 5 the junction between the folds 12 and the slit 10 to a point on the upper outer edge of the said flap 16, substantially opposite that edge of the tongue 23, as shown in Figs. 2 and 3.

10 When the parts are brought together in position, as shown in Fig. 1, the box is set up and locked. When the box is set up as shown in Fig. 1, and a strain or pressure is put on the box, the pressure will cause the 15 corner flap 16 to bend at the crease 17 and this bending will cause the flap 20 and the tongue 23 to become more tightly engaged, and the locking device will then become stronger and have a greater resistance. The 20 bending at the crease 17 twists the tongue in the slot 24, holding the tongue 23 tighter in the slot 24 by being thus twisted; and, when so twisted, causing the outer edges of the tongue 23 to be more tightly engaged by that 25 part of the flap 20 between the edge of the slot 24 and the lower edge of the flap 20; and, also by the upper edge of the slot 24 pressing against the tongue 23. The crease or fold 17, or one similar thereto, is a necessary part in setting up and knocking down 30 a paper box of this or similar construction and is ordinarily the weakest part of the box, but with the adaptation of the locking device described herein, the crease 17 becomes an element in the locking device and 35 one of the strengthening features after the box is set up when a strain or pressure is applied.

The top of the box is a duplicate of the 40 main part of the box and formed in the same manner, and needs no special illustration or description.

In Fig. 7, the structure shown is substantially the same as that shown in the 45 principal views, except the staples 21 are omitted, the stiffening member 25 is only the width of the folding member 20 of the ends, and the tongues 23 are relied upon to maintain the end in its erected position.

50 Having thus fully described my said invention, what I claim as new and desire to secure by Letters Patent, is:

1. A collapsible box formed of a blank of appropriate material creased along the lines 55 of the folds between the bottom and the sides and ends of the box, the ends of said box beyond said folds being of a length greater than the normal height of the box and formed with slits from the outer ends 60 of the fold between the end and the bottom of the box along the lines of the fold between the bottom and sides, the end portions between said slits being reinforced with a

central stiffening strip and formed to fold along the line of the normal height of the 65 box over onto said stiffening strip, the corners formed by the ends of the sides of the box being folded diagonally from the juncture at the corner between the side and the bottom to the outside at a point in line 70 with the normal height of the box, said corners being folded along said crease and then the sides folded over onto the top face of the bottom, then the outer flap on the extreme end being folded over onto the several 75 parts and secured by staples driven through the several thicknesses, said corner flaps of the sides being formed with tongues adapted to be bent upwardly and inserted through slots in the outer fold of the end pieces, all 80 substantially as set forth.

2. A collapsible box formed of a board creased along the lines marking the junction between the normal bottom, ends and sides of the box, folds on the ends of the 85 box having slots to fit tongues cut from end flaps, end flaps formed from the sides outside the normal length of the box, said end flaps having tongues cut therefrom and having diagonal creases or folds extending from 90 the corner between the sides and the bottom to a point on the upper outer edge of said end flaps substantially opposite that edge of the tongue nearest the end of said end flaps, the several parts when brought 95 together in position forming a permanent fastening device, substantially as set forth.

3. A collapsible box formed of appropriate material creased along the lines marking the junction between the normal bottom, sides and ends of the box, slits being formed to divide the ends from the sides, the ends of said box beyond said creases being of a length greater than the normal height of the box and formed with slots in the outer 100 ends to the creases between the end and the bottom of the box along the lines of the fold between the bottom and sides, end flaps formed from the sides outside the normal length of the box, tongues cut from end flaps, diagonal folds or creases extending from the corner between the sides and bottom to the top of the end flaps at a point in line with the normal height of the box, the several 105 parts when brought together forming a permanent locking device, substantially as set forth.

In witness whereof, I have hereunto set my hand and seal at Memphis, Tennessee, this 25th day of January, A. D. nineteen 110 hundred and fifteen.

FRANK H. HOUGHLAND. [L.S.]
